UNITED STATES PATENT OFFICE.

WILLIAM D. CHASE, OF BROOKLYN, ASSIGNOR TO HIMSELF AND GEORGE W. ALMY, OF SAME PLACE, AND HARVEY S. ALMY, OF NEW YORK, N. Y.

DESIGN FOR CLOCK-CASE.

SPECIFICATION forming part of Design No. 11,717, dated April 6, 1880.

Application filed February 19, 1880. Term of patent 7 years.

To all whom it may concern:

Be it known that I, WILLIAM D. CHASE, of Brooklyn, in the county of Kings and State of New York, have invented a new and original Design for a Clock-Case, of which the following is a specification.

My invention relates to a new and original design for clock-cases; and it consists in the new configuration of the case, as hereinafter described.

The accompanying drawing represents a perspective view of my improved design.

The design consists of a case, A, formed of representations of staves *a*, hoops *b*, and a depressed top, *b'*, like the head of a barrel, so as to form a case to represent a barrel or keg. Into the side thereof is set the face B of the clock.

I claim—

1. The design for a clock-case, consisting of the case A, of the form of a barrel or keg, composed of representations of staves *a* and hoops *b*, substantially as shown.

2. The design for a clock-case, consisting of a keg-shaped body having the depressed top *b'*, substantially as shown.

3. The design for a clock-case, consisting of the case A, of the form of a barrel or keg, having the representations of staves *a*, hoops *b*, and depressed top or head *b'*, substantially as shown.

WILLIAM D. CHASE.
